 graphie m. b. H., Berlin, Germany, a corpora-
 tion of Germany

Application January 4, 1938, Serial No. 249,238
 In Germany January 19, 1938

7 Claims. (Cl. 179—171)

This invention relates to amplifying apparatus, and will be explained more fully by reference to the appended drawing, wherein Figure 1 shows an exemplified embodiment of a circuit arrangement in which the steps here disclosed have been adopted, and Figure 2 shows the identical scheme in the form of a bridge arrangement so that the effect and operation of the invention may be understood more clearly.

It is known in the prior art according to Fig. 1 to tap the grid biasing potential for a tube across a resistance W_1 which is traversed by the plate current of all tubes. Inasmuch as in the resistance W_1 there still exists an alternating potential originating from the supply-line or mains (ripple), the smoothing means indicated by the dash-lines is connected between the grid leak R_g and resistance W_1 , or at least resistance W_1 is bridged or shunted by a condenser. Now, according to the invention, the said smoothing means is rendered dispensable. Especially in small-sized receiver sets, for instance, single circuit receivers comprising two tubes, the resultant saving means so much that the use of the invention is noticeable to an appreciable extent in the reduction of the total cost of the receiver. What is essential is that in using the invention, none of the compensation circuit organizations known in the prior art are utilized which require additional circuit elements or in which smoothing means must be dimensioned to insure compensation of hum.

The invention is concerned with a receiver or amplifier with mains connection which comprises at least two resistance-coupled tubes with a resistance (W_1) included in the joint plate lead at the mains end of the last smoothing condenser (C_2) for the negative grid biasing potential of the second tube which is not to be filtered any more.

According to the invention, the coupling elements of the resistance amplifier stage (R_a , C_1 , R_g) and the resistance W_1 for the negative grid biasing voltage of the second tube and the last smoothing condenser (C_2) in comparison to the inner resistances of the two tubes (I, II) are so dimensioned that such disturbing alternating potential as may still prevail between the positive pole ($+A'$) of the smoothed plate potential for both tubes and the negative end ($-A$) of the biasing voltage resistance, and which acts in the bridge arrangement formed by all of the said circuit elements will not allow any essential alternating voltage to arise between the grid-filament

path (GK) of the second tube (II) forming the bridge diagonal.

In the arrangement in Fig. 1, tube I which, for instance, may be connected as an amplifying detector, is in coupling relation with tube II by the resistance coupling elements R_a , C_1 , R_g . The unsmoothed plate D. C. voltage originating from the D. C. supply line or mains or from a rectifier in case of an A. C. supply line, is connected across the terminals $-A$ and $+A$ and it is smoothed by the aid of the condenser C_3 , C_2 and resistance W_2 . Across the resistance W_1 , as stated, arises the grid biasing potential for the power tube. The screen grid of the power tube is united with the positive pole $+A'$ of the smoothed plate potential.

In the bridge arrangement shown in Fig. 2 the same denotations are used in Fig. 1, with the addition of the values which have been ascertained by test in a particular circuit. The inner resistance of the tube I as well as the inner resistance of the cathode-screen-grid path of tube II were each around 50,000 ohms. The inner resistance of the filament-plate path of power tube II, as will be seen, is so high that it may be neglected in comparison with the bridge balance. The various circuit elements are so dimensioned that a disturbing or stray alternating potential existing across $-A$ and $+A'$ will no longer exist across G and K. It will be remembered that an alternating potential at this particular place is very undesirable for the reason that it would be still further amplified by the power tube II. A disturbing alternating voltage arising at tube I will no longer manifest itself seeing that the bridge is so balanced that the alternating potential between grid and filament of tube II no longer exists. For this reason, a distinct smoothing means for the plate current of tube I is dispensable. Any rest or trace of alternating potential which may still prevail at the condenser C_2 , as a result of control of the screen grid of tube II, will permit only a very small plate alternating current to arise, so small, indeed, that it is practically inaudible; but if the bridge is properly adjusted it may also be balanced out.

The dimensions chosen for the circuit organization Fig. 1 differs from the scheme known in the earlier art insofar as the first tube has a comparatively high internal resistance, and that, moreover, the coupling condenser C_1 is fairly small, and the grid leak resistance R_g somewhat higher than normally. The lower cut-off frequency of the coupling element, however, still

lies at 50 cps so that the low frequencies are not unduly attenuated. The other quantities contained in the bridge, of course, are also decisive for the operation of the invention.

In the case of direct current and universal receivers, as is well known in the art, a condenser C_4 is connected between the cathode and the ground according to Fig. 1, in order to ground the cathode for RF. The said condenser enters into the bridge scheme in a way as indicated in Fig. 2 when terminal -A is united with the grounded pole of the network. Experiments have demonstrated that for dimensions as indicated in the drawing (Fig. 2) for the various circuit elements, the said condenser will still further reduce the line hum to a slight extent. To be sure, the effect is not very essential so that the circuit organization is useful also in cases where terminal +A is united with the grounded pole of the mains. In this case, the condenser is connected between points K and +A, Fig. 2.

Where the line-supply potential is less than 200 V, the internal resistance of the tubes will have somewhat different values; however, practical tests have shown that, because the gain is at the same time somewhat lower, the effect and usefulness of the invention will still be adequate.

I claim:

1. In signalling apparatus including a first electronic tube having an anode, a cathode and a signal grid, means for impressing signal energy between the signal grid and cathode, a pair of terminals adapted to be connected to a source of direct current having an undesired hum component, one of said terminals constituting a positive terminal and the other thereof a negative terminal, an anode resistor connected between the positive terminal and said anode, a second tube having an anode, a cathode, a signal grid and a screen grid, a coupling condenser connected between the anode of the first tube and the signal grid of the second tube, a utilizing device connected between the anode of the second tube and said positive terminal, means for connecting the screen grid to said positive terminal, a cathode resistor connected between the negative terminal and both of said cathodes whereby anode current from both of said tubes flows through said cathode resistor, means including at least a part of said cathode resistor and a grid leak resistor in series for connecting the signal grid of said second tube to the cathode thereof whereby said last named signal grid is biased with respect to said last named cathode at least in part by current flowing through said cathode resistor, said cathode resistor also having flowing therethrough an undesired hum component from said source whereby said hum component is impressed upon the cathode of said second tube, and means for impressing a substantially similar hum component derived from said source upon the signal grid electrode of said second tube to thereby substantially neutralize the effect of the hum component impressed upon the cathode.

2. In amplifying apparatus, a screen grid tube, a four-arm balanced bridge network having a first arm including a cathode resistor, a second arm adjacent said first arm including a grid leak resistor, a third arm opposite the first arm including a coupling condenser in series with a plate resistor, and a fourth arm opposite the second arm including a filter condenser shunted by the cathode-screen-grid path of said screen grid tube, means for connecting a source of energizing voltage between a point of the bridge com-

mon to the first and second arms therof and a point of the bridge common to the third and fourth arms thereof, means connecting the cathode of said tube to a point of the bridge circuit common to the first and fourth arms, means for coupling the input grid of the screen grid tube to a point of the bridge common to the second and third arms whereby the input grid-cathode circuit of said tube forms a diagonal of the bridge, a driver stage for said screen grid tube comprising an electronic tube having an anode, a cathode, and a grid electrode, means for connecting the anode to a point of said third arm which is common to the coupling condenser and the plate resistor therein, means for connecting the cathode to a point of the bridge which is common to the first and fourth arms thereof and means for coupling a source of energy to be amplified between the grid and cathode of said driver tube.

3. In amplifying apparatus, a first tube having an anode, a cathode and a grid, a signal input circuit for said first tube connected between the grid and cathode thereof, a source of fluctuating current, an output circuit for said first tube including a plate resistor, said source of said fluctuating current and a cathode resistor in series connected between the anode and cathode thereof, a second tube provided with an anode, a cathode and a grid electrode, means including a coupling condenser for connecting a point of the output circuit of the first tube to said last named grid electrode, means for biasing the grid electrode of said second tube with respect to the cathode thereof comprising a connection between said grid and cathode including in series a grid leak and said cathode resistor, an output circuit for said second tube comprising a utilizing device, said source of fluctuating current and said cathode resistor all connected in series in the order named between the anode and cathode thereof, a filter condenser connected between the source end of the utilizing device and the cathode, fluctuations from said source being impressed upon the output circuit of the first tube, the output circuit of the second tube and the input circuit of the second tube, said coupling condenser and plate resistor, said grid leak resistor, said cathode resistor, and said filter condenser being proportioned so that substantially the same fluctuating component is impressed up on the grid electrode of said second tube as on the cathode thereof whereby the effect of the fluctuating component is neutralized.

4. In amplifying apparatus, a first tube having an input circuit and an output circuit, said output circuit including an anode resistance, a source of fluctuating current and a cathode resistance in series, whereby in the operation of said apparatus there exists in said output circuit the fluctuating component of said source, a second tube having a grid circuit including a grid leak resistor and said cathode resistor in series, a coupling condenser connecting a point of said anode resistor to a point of said grid circuit through which coupling the fluctuating component in said output circuit is transferred to said grid circuit, an output circuit for said second named tube including in series a utilizing device, the source of fluctuating current and the cathode resistor, said last named tube having impressed upon its grid circuit a fluctuating current component due to the inclusion of said cathode resistor in said grid circuit, said coupling condenser and grid leak resistor being proportioned in relation to said anode resistance,

cathode resistance and filter condenser so that the effect of the fluctuating components upon said second tube is substantially eliminated.

5. In amplifying apparatus, a first tube having an anode, a grid electrode and a cathode, means for impressing signal voltage between the grid electrode and cathode of said tube, an output circuit for said tube comprising an output impedance, a source of direct current, the output of which has an undesired hum component, and a cathode resistor in series and in the order named between the anode and cathode of the tube, a filter condenser connected between the source end of the output impedance and the cathode, a second tube having an anode, a cathode, a signal grid and an auxiliary grid, a coupling condenser connected between a point of said output impedance and said signal grid, a signal grid-cathode circuit for said second tube including a grid leak resistor and at least a portion of said cathode resistor in series, an auxiliary grid-cathode circuit for said second tube including said source of direct current and said cathode resistor in series, and an anode-cathode circuit for said second tube including a load device, said source of direct current and said cathode resistor in series, said cathode resistor, said grid leak resistor, said coupling condenser in series with said output impedances and said filter condenser shunted by the internal screen grid-cathode impedance of said second tube constituting four arms of a balanced bridge arrangement wherein the signal grid of the second tube is connected to the junction point of the arm of the bridge constituted by said grid leak resistor and the arm constituted by the coupling condenser in series with the output impedance, and the cathode of the second tube is connected to the junction point of the arm constituted by

the cathode resistor and the arm of the bridge which includes the filter condenser, said source of direct current being effectively connected across the other two opposite junction points of the bridge whereby substantially equal hum voltages are produced on the signal grid and cathode of the second tube.

10 6. In amplifying apparatus including a utilizing device and an amplifier tube, said amplifier tube being provided with an anode, a cathode and a grid electrode, a four arm balanced bridge circuit, one of the arms thereof including an impedance and a condenser in series, an arm adjacent said first arm including an impedance element, the other arm adjacent said first arm including a condenser shunted by a circuit including the utilizing device and said amplifier tube in series, the arm opposite the first named arm of the bridge including an impedance element, a source of fluctuating direct current potential connected between a point common to said first named arm and said second named adjacent arm and a point common to said first named adjacent arm and said opposite arm, a driver stage for said tube including an electronic tube having an anode, a cathode and a signal grid, and means including said first named condenser for connecting the anode of said last named tube to the signal grid of the first named tube.

15 20 25 30 35 7. In the arrangement described in claim 6, means including the impedance element in the arm opposite the first named arm for connecting the cathode of said driver tube to one terminal of the source, and means including the impedance element in said first named arm of the bridge for connecting the anode of said driver tube to the other terminal of the source.

HANS DUBBERKE.
